UNITED STATES PATENT OFFICE.

HUGH M. BARR, OF PENSACOLA, FLORIDA.

RETORT.

1,373,702.

Specification of Letters Patent.

Patented Apr. 5, 1921.

Application filed May 24, 1920. Serial No. 383,742.

To all whom it may concern:

Be it known that I, HUGH M. BARR, a citizen of the United States, and a resident of Pensacola, in the county of Escambia and 5 State of Florida, have invented a new and useful Improvement in Retorts, of which the following is a specification.

My invention relates to retorts especially adapted for the destructive distillation of 10 wood.

The object of the invention is to provide a retort of this character which is capable of efficiently carrying out the process of distillation without the employment of cumbersome and unyielding jackets of brickwork, concrete or other masonry thereby eliminating the damaging and deleterious effects due to the ruptures or cracks that occur in the masonry.

20 Another important object is to provide a retort of this character with improved heating means which is embodied in and associated with the structure of the retort in such manner that the high degree of heat 25 requisite to successful operation of the retort may be attained without exposing the contents of the retort to contact with the gases of combustion.

Another object is to provide a retort of simple and durable construction, reliable in operation and easy and inexpensive to manufacture.

Other objects and advantages reside in the certain novel features of the construction, arrangement and combination of parts which will be hereinafter more fully described and particularly pointed out in the appended claims, reference being had to the accompanying drawings forming a part of 35 this specification, and in which—

Figure 1 is a vertical longitudinal section of the retort,

Fig. 2 is a transverse vertical section of the retort,

40 Fig. 3 is an end elevation,

Fig. 4 is a horizontal section of the means for floating the floating flue section, and

Fig. 5 is a transverse vertical section thereof.

50 Referring to the drawings wherein is shown a preferred embodiment of my invention the retort is designated generally at A and a condenser designated at B of conventional construction is connected by the conduit C to the retort.

The retort A comprises a metallic shell 10

preferably constructed of sheet iron and having an inverted U cross section. The top, bottom, side and end walls of the shell are, in general, of solid imperforate metal except that one of the end walls is provided with a removable door 11.

The interior of the metallic shell is provided with a lining 12 of asbestos which is exposed to contact with the volatile products of the wood which harden and render refractory the asbestos. A plurality of rivets 65 or suitable fastening means 13 extend through the asbestos and the metallic shell to secure the asbestos and shell together. 70 These rivets are so distributed as to exert a securing action evenly throughout the area of the lining and the shell.

A false bottom 14 of reticulated or foraminous metal is secured to the walls of the retort and defines with the inner walls of the retort a retort chamber 15 and a heating chamber 16. Rails 17 arranged upon the upper surface of the false bottom 14 are adapted to receive the carriage 18 which 80 carries the wood to be distilled.

Means are provided for heating the retort without exposing the contents of the retort chamber to contact with the gases of combustion. This means consists of a pair of 85 flues 19 extending longitudinally of the heating chamber. Each of these flues comprises two stationary flue sections 20 and 21 carried respectively by the front and rear end walls of the metallic shell, the stationary 90 section 20 being alined with the stationary section 21 of the opposite wall. The stationary section 20 leads to the furnace or other source of heat 22 and the stationary section 21 leads by a branch 23 to the stack 24. 95 Both stationary flue sections 20 and 21 are of such material or are so insulated as not to radiate heat. A floating flue section 25 is arranged within the heating chamber between the stationary flue sections 20 and 21 100 and is spaced from the walls of the heating chamber. The floating flue section 25 is of metallic construction and is adapted to freely conduct and radiate the heat.

The section 25 is suspended from each of 105 the stationary sections by floating means which consists of an inner sectional sleeve of asbestos indicated at 26 (see Figs. 4 and 5) and an outer sectional sleeve 27 of thin sheet metal, the joints of which are staggered with respect to the joints of the asbestos sleeve 26. The sleeves 26 and 27 are

each convexed centrally as shown at 28. Clamping bands 29 cooperate with the end portions of the sleeves to secure the sleeves to the adjacent ends of the stationary and 5 floating flue sections respectively.

The retort is preferably mounted upon axles 30 carrying wheels 31 at their ends whereby the retort is made portable and may be moved from place to place.

10 A crane 32 including a swinging boom 33 and a traveling block 34 is carried by the top of the retort and is adapted to be utilized in the removal of the door 11 and for other purposes in conjunction with the operation 15 of the retort.

In practice it has been found that when the sheet metal of the shell which comprises the retort is lined with asbestos and the asbestos is secured thereto in the manner described, the volatile products of the wood 20 permeate the asbestos and harden and render the same refractory. Any expansion or contraction of the metal of the retort is communicated through the securing means to 25 the asbestos which after the action of the volatile products of the wood, partakes of the expansion and contraction of the iron through the action of the securing means.

When the retort is in operation the gases 30 of combustion from the furnace 22 flow through the stationary flue sections 20, through the floating flue sections 23, through the stationary flue sections 21 and branches 23 to the stack. The floating sections are 35 heated to a white heat, and being freely suspended, diffuse the heat to best advantage and thereby efficiently heat the retort chamber. The means for floating the flue section 25 not only serve to suspend the same spaced 40 from the walls of the heating chamber but also permit of the free expansion and contraction thereof as the ends thereof are free to partake of the movement incident thereto.

The retort constructed in accordance with 45 my invention is endowed with the feature of portability and may thus be utilized at the source of supply of the wood.

I claim:

1. A retort for the destructive distillation 50 of wood comprising a metallic shell, a lining of asbestos for said shell, a false bottom of reticulated material defining a retort chamber in the upper portion of the metallic shell and a heating chamber in 55 the lower portion of the metallic shell and means for heating the retort comprising a pair of flues extending longitudinally of the heating chamber, each of said flues including two stationary flue sections 60 alined with each other, one of said sections being seated in one wall of the shell and leading to the source of heat and the other of said sections being seated in the opposite wall of the shell and leading to the stack,

a floating flue section suspended within the 65 heating chamber between the stationary sections and spaced from the walls of the heating chamber and means for floating said floating flue section including a split asbestos sleeve having a centrally convexed portion, a split metallic sleeve having a correspondingly convexed central portion and clamping bands for securing the ends of the sleeve to the respective flue sections.

2. A retort for the destructive distillation 70 of wood having a retort chamber and a heating chamber and means for heating the retort comprising a pair of flues extending longitudinally of the heating chamber, each of said flues including a stationary flue section 80 and a floating flue section suspended within the heating chamber and spaced from the walls thereof and means for floating said floating section including a split asbestos sleeve, a split metallic sleeve and a clamping 85 band.

3. A retort for the destructive distillation 90 of wood including a retort chamber and heating chamber and means for heating the retort including a floating flue section suspended within the heating chamber and spaced from the walls thereof and means for floating said flue section including an inner asbestos sleeve having a central convexed portion, an outer split metallic sleeve incasing 95 said split asbestos sleeve and clamping bands for the ends of said sleeves.

4. A retort for the destructive distillation 100 of wood comprising a metallic shell and an asbestos lining for said shell, means for securing the asbestos lining to the metallic shell and means for heating the retort including a floating flue section suspended within the metallic shell.

5. A retort for the destructive distillation 105 of wood comprising a metallic shell and an asbestos lining for said shell exposed to contact with the volatile products of the wood to be thereby hardened and rendered refractory, all as and for the purposes set 110 forth.

6. A retort for the destructive distillation 115 of wood comprising a metallic shell and an asbestos lining for said shell exposed to contact with the volatile products of the wood to be thereby hardened and rendered refractory, means for securing the asbestos lining to the metallic shell and arranged to exert a securing action evenly through the area of the lining and shell, all as and for 120 the purposes set forth.

7. A portable retort for the destructive distillation of wood comprising a metallic shell, an asbestos lining for said shell and wheels carrying said metallic shell.

8. A retort for the destructive distillation 125 of wood comprising a metallic shell having a retort chamber and a heating chamber and

means for heating the retort including two stationary flue sections alined with each other, one of said sections being seated in one wall of the shell and leading to the 5 source of heat and the other of said sections being seated in the opposite wall of the shell and leading to the stack, a floating flue section suspended within the heating chamber between the stationary sections and spaced 10 from the walls of the heating chamber and means for floating said floating flue section including a split asbestos sleeve having a centrally convexed portion, a split metallic sleeve having a correspondingly convexed 15 central portion and clamping bands for se-

curing the ends of the sleeve to the respective flue section.

9. A retort for the destructive distillation of wood having a retort chamber and a heating chamber and means for heating the retort including a floating flue section suspended within the heating chamber and spaced from the walls thereof and means for floating said floating flue section including an asbestos sleeve having a centrally convexed portion, a metallic sleeve having a correspondingly convexed portion and a clamping band for the ends of said sleeve. 20 25
